R. B. BAKER,
LICENSE PLATE CARRIER AND SIGNAL,
APPLICATION FILED SEPT. 12, 1914.

1,163,199.

Patented Dec. 7, 1915.

UNITED STATES PATENT OFFICE.

RALPH B. BAKER, OF GALION, OHIO.

LICENSE-PLATE CARRIER AND SIGNAL.

1,163,199.

Specification of Letters Patent.

Patented Dec. 7, 1915.

Application filed September 12, 1914. Serial No. 861,363.

To all whom it may concern:

Be it known that I, RALPH B. BAKER, a citizen of the United States, residing at Galion, in the county of Crawford and State of Ohio, have invented a certain new and useful Improvement in License-Plate Carriers and Signals, of which the following is a specification.

The invention relates to carriers for the license-plates of motor vehicles and the like, and to means in connection therewith for indicating to a following vehicle an intention to change the direction of travel or to stop.

The main object of the invention is to provide simple, inexpensive, easily operated means carried by the license-plate holder for displaying a signal adjacent to such plate which will indicate such intention.

Another important object is to provide means for moving the usual tail-light for such signal, and a further object is to provide a conspicuously displayed day signal operated by the same mechanism.

A further important object is to provide an electric motor mounted on the carrier to impart the desired movements, with means for permitting the motor to run idly when the display movement is completed and the current still maintained, thus avoiding injury to the motor.

The invention consists in certain novel features and details of construction and arrangement by which the above objects are attained, to be hereinafter described and claimed.

The accompanying drawings form a part of this specification and show an approved form of the invention.

Figure 1 is a rear elevation of an automobile equipped with the improved plate carrier, showing the signals displayed. The remaining figures are on a larger scale. Fig. 2 is an elevation of the plate carrier and license-plate, with its signals undisplayed. Fig. 3 is a corresponding plan view. Fig. 4 is a rear elevation corresponding to Fig. 2. Fig. 5 is a vertical transverse section taken on the line 5—5 in Fig. 4. Fig. 6 is an elevation of the signal-carrying bar and its motor pinion alone.

Similar letters of reference indicate the same parts in all the figures.

A is a plate forming the rear exterior face of the carrier, and projecting at one end slightly beyond the license-plate M carried

thereon. Attached to the rear or inner face of the plate A are two longitudinally extending parallel strips A¹ A² serving as guides for an endwise movable bar C mounted between them and carrying on its projecting end a tail-light B which may be understood to be an electric lamp of any approved type arranged to illuminate the license-plate and show a rear danger signal as usual. The bar C is held between the guides by a cover A⁴ inclosing portions of the latter and of the bar, and its inward movement is limited by a stop C¹ on the inner face of the bar, adapted to contact with the edge of such cover. The lower edge of the bar is toothed to form a rack C² and is engaged by a pinion D¹ of a small electric motor D mounted on the cover A⁴, controlled by a push-button or other switch D² located near the seat or at any point in the car conveniently placed for operation by the driver. The motor D is so wound and connected as to rotate the pinion D¹ in the direction to force the bar C outwardly in opposition to the force of a helical spring E attached at one end to the slide or bar at the point e and lying within the bar which is hollowed as at e to receive it, and at the other end to a pin A³ on the inner face of the carrier-plate A. The outward movement of the bar is limited by a cross-bar or stop C⁴ arranged to strike the inner edge of the cover A⁴.

The bar or slide C lies normally in the inward position indicated by the full lines in Figs. 2, 3 and 4 in which position the tail-light B stands close to the end of the license-plate M and illuminates the latter and shows a red light at the rear as usual. When it is intended to stop or to change the direction of travel the driver presses the button D² and starts the motor D which by the meshing of its pinion D¹ with the rack C² immediately moves the slide and carries the tail-light B from the license-plate, but without materially lessening its illumination, a movement easily seen by the drivers of following vehicles. On releasing the button the slide is again drawn inwardly by the contractile force of the spring E and the operation may be repeated to produce a to-and-fro or reciprocatory movement as often as deemed necessary to insure observation. This movement of the tail-light is exceedingly noticeable at night and is likely to be

observed in daylight but to insure an equally conspicuous day signal a strip or flag F of flexible material, preferably red glazed oiled fabric, is provided, wound upon a vertical spring roller F¹ supported in lugs A⁵ A⁵ on the upper and lower edges of the plate A, with its free end attached to the bar C at C³. The roller F¹ is of any desired construction adapted to rewind automatically the strip or flag F, and when the latter is displayed by the outward movement of the bar aids the spring E in returning the bar. The flag is also plainly visible at night by reason of its illumination by the adjacent tail-light.

In order to relieve the motor D and permit it to run after the bar C has moved to the full extent of its outward throw and thus avoid burning out, a recess c¹ is provided at the inner end of the rack in which the pinion D¹ may revolve idly until the push-button D² is released. On thus cutting off the current the pinion D¹ and its motor armature offers no resistance to the return movement induced by the spring E.

Flexible electric connections are provided to permit the tail-light to be reciprocated with the bar C without breaking its lighting circuit, and it will be understood that batteries, not shown, or other sources of electric energy are provided, both for the tail-light and for the motor B.

The carrier may be supported upon the vehicle by any suitable means as by a bracket G only partially shown, and may be mounted on the body at any desired location or on one of the rear mudguards, as indicated by dotted lines in Fig. 1, or at any selected point.

Either the tail-light B or flag F may be omitted relying upon the remaining signal to give the desired warnings; and the device may be used independently of the license-plate, but it is preferred for reasons of economy and convenience to utilize the plate carrier to contain the mechanism, and the tail-light as a signal. Other types of lamps may be substituted for the tail-light.

Other modifications may be made in the forms and proportion of the parts and in the arrangement of the operating mechanism without departing from the invention.

I claim:

1. A carrier adapted to display a license-plate mounted thereon, a tail-light slidably toward and away from said license plate and arranged to illuminate said plate and show a rear signal and carried by said carrier adjacent to said plate, an electric motor and mechanism in said carrier for moving said tail-light relatively to said plate.

2. A carrier adapted to display a license-plate mounted thereon, a bar slidably mounted in said carrier, a rack on said bar, a signal carried by the latter, an electric motor in said carrier, a pinion on said motor in

mesh with said rack, and connections from said motor to a switch for energizing said motor and thereby moving said signal relatively to said plate.

3. A carrier adapted to display a license-plate mounted thereon, a bar slidably mounted in said carrier, a rack on said bar, a signal thereon, stops on said bar and carrier for limiting the longitudinal movement of said bar in each direction, an electric motor having a pinion in mesh with said rack, the latter having a recess in which said pinion may revolve idly at the end of one extreme movement of said bar, and a spring for returning said bar.

4. A carrier adapted to display a license-plate mounted thereon, a bar slidably mounted in said carrier, a rack on said bar, a tail-light thereon adapted to illuminate said plate and to show a rear signal, stops on said bar and carrier for limiting the longitudinal movement of said bar in each direction, an electric motor having a pinion in mesh with said rack, the latter having a recess in which said pinion may revolve idly at the end of one extreme movement of said bar, and a spring for returning said bar.

5. In a device of the character set forth, a carrier, a bar slidably mounted therein, a roller on said carrier, a flag on said roller arranged to be automatically wound thereon and having its free end secured to said bar, a tail light movable with said bar as the flag is wound or unwound, and electric mechanism in said carrier for moving said bar and unwinding and displaying said flag.

6. In a device of the character set forth, a carrier, a bar slidably mounted therein, a rack on said bar, a roller on said carrier, a flag on said roller arranged to be automatically wound thereon and having its free end secured to said bar, stops on said bar and carrier for limiting the longitudinal movement of said bar in each direction, an electric motor having a pinion in mesh with said rack, the latter having a recess in which said pinion may revolve idly at the end of one extreme movement of said bar, and a spring for returning said bar.

7. In a device of the character set forth, a carrier, a bar slidably mounted therein, a roller on said carrier, a flag on said roller arranged to be automatically wound thereon and having its free end secured to said bar, electric mechanism in said carrier for moving said bar and unwinding and displaying said flag, and a lamp mounted on said bar and arranged to illuminate said flag.

8. A carrier adapted to display a license-plate mounted thereon, a bar slidably mounted in said carrier, a roller on said carrier, a flag on said roller arranged to be automatically wound thereon and having its free end secured to said bar, electric mechanism in said carrier for moving said bar and un-

winding and displaying said flag, and a tail-light carried by said bar and adapted to illuminate said flag and plate and to show a rear signal.

- 5 9. A carrier adapted to display a license-plate mounted thereon, a bar slidably mounted in said carrier, a rack on said bar, a roller on said carrier, a flag on said roller arranged to be automatically wound thereon and having its free end secured to said bar, a tail-light on said bar adapted to illuminate said plate and flag and show a rear signal, stops on said bar and carrier for limiting the longitudinal movement of said bar in each

direction, an electric motor having a pinion 15 in mesh with said rack for moving said bar and unwinding and displaying said flag, said rack having a recess in which said pinion may revolve idly at the end of the extreme flag-displaying movement of said bar, 20 and a spring for returning said bar.

In testimony that I claim the invention above set forth I affix my signature, in presence of two witnesses.

RALPH B. BAKER.
